UNITED STATES PATENT OFFICE.

JOSEPH H. SCHARFF, OF NUTLEY, NEW JERSEY.

THERMOSTATIC CIRCUIT CLOSER.

Application filed July 29, 1918, Serial No. 247,279. Renewed November 3, 1923.

To all whom it may concern:

Be it known that I, JOSEPH H. SCHARFF, a citizen of the United States, residing at Nutley, in the county of Essex and State of New Jersey, have invented certain new and useful Improvements in Thermostatic Circuit Closers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

My invention relates to improvements in fire alarm systems and more particularly to systems of the pneumatic-compensating type, and the object has been to produce such a system, and a detector therefor, which shall possess great reliability and certainty of operation, being so designed as to possess effective means for preventing the sending of false alarms, while, at the same time, assuring an immediate alarm in all cases where true fire conditions occur.

Pneumatic-compensating fire-alarm systems heretofore in general use have included a long metallic tube which extended throughout the area to be protected, one end of the tube generally being closed and the other end connected with an indicator element in the form of a flexible diaphragm having a movable contact adapted to complete an electric alarm circuit upon sufficient increase of air pressure inside the tubing. These systems have also been provided with a leak disposed adjacent the diaphragm for the purpose of permitting air to be taken into or discharged from the system to equalize air pressure upon slow changes in temperature such as ordinarily occur.

These systems are readily adapted to send in fire alarms upon an increase in temperature in the protected area above a predetermined rate, say three and one-half degrees a minute. But these systems have been found to be extremely sensitive in that alarms are given every time the temperature rise is above the predetermined rate, irrespective of whether this rise is occasioned by fire conditions or by some temporary event introducing no fire risk. Such temporary conditions cannot be avoided in industrial plants, such, for example, as forge shops and foundries, in boiler rooms, etc., where a sudden rise in temperature continues for

only a short time but at a sufficiently high rate to actuate the diaphragm. This results in sending in a false alarm, and the recurrence of these false alarms tends to destroy confidence in an installation. The frequency of these false alarms has to some extent hindered the commercial development of a system which, under proper operating conditions, will unfailingly send in an alarm whenever fire conditions bring about a continued increase in temperature.

I have found that the sending in of these false alarms is caused by the inability of a simple leak, even when properly adjusted for fire conditions, to permit the escape of expanded air caused by such temporary rises in temperature as must be expected in many locations. The inter-relations between the leak and diaphragm are so critical that the systems heretofore available have been incapable of always discriminating between rises in temperature caused by fire conditions and those caused by temporary conditions, and have almost invariably sent in alarms when the rate of temperature rise is above that predetermined by the adjustment of the leak.

The present invention is directed to the provision of an improved pneumatic-compensating fire-alarm system which is provided with suitable means for absorbing the temporary or sudden air movements which are caused when there is no fire risk. The invention contemplates an improved method of controlling the air pressure brought about by rises in temperature and indicating and announcing only those movements which are indicative of fire conditions.

It also has been found in practice that frequently "shock" impulses are sent through the tubing employed with pneumatic fire-alarm systems, arising from what may be considered the usual normal and natural temperature changes, such, for example, as occur above banks of steam-heating pipes, so that such impulse or impulses might cause to be registered an alarm when no fire conditions exist; and with this also in view and to overcome this objectional feature is another object of the present invention.

A further object of the invention is to provide in connection with a fire or temperature alarm of the pneumatic type, means for preventing water forming in the tubing, field-practice having brought out

the fact that water may form in the tubing, such collection of water preventing in the tubing the natural and unrestricted expansion of the air in such tubing, so that when 5 water so formed is located in certain places, slight temperature changes tend to produce "false" alarms.

With this in view, I provide the air-intake or intakes of the detector-device with 10 means through which the air which is taken into the system has to pass through a hygroscopic material, so that the air taken into the system will be dry; and, furthermore, to provide in connection with said intake 15 or intakes means which will prevent dust from entering and clogging the intake or leak ducts or the tubing.

Other objects of the present invention not at this time more particularly enumerated 20 will be more fully understood from the following detailed description of the present invention.

With these various objects in view, and to produce entirely new physical and mechanical effects, my present invention consists, primarily, in the novel fire or temperature alarm-system and detector therefor and hereinafter more fully set forth; and, the said invention consists, further 25 more, in the novel arrangements and combinations of the several devices and parts, as well as in the details of the construction of the said parts, all of which will be more fully described in the following specification, and then finally embodied in the clauses of the claims which are appended to the said specification and form an essential part of the same.

One of the many possible embodiments 40 of the present fire alarm system and of certain of the devices for use therein, is shown, for purposes of illustration, in the accompanying drawings, in which—

Figure 1 is a view showing diagrammatically a fire-alarm system of the pneumatic type and novel detector therefor, the same illustrating one embodiment of the principles of the present invention; Figure 2 is a vertical sectional view taken on line 50 2—2 in said Figure 1, looking toward the left; and

Figure 3 is a vertical sectional representation of the detector, said view being drawn on an enlarged scale.

Similar characters of reference are employed in the said above described views, to indicate corresponding parts.

Referring now to the several figures of the drawings, the reference-character 1 indicates the complete detector. A suitable base or support 2 is provided upon which are mounted and secured thereon, by means of screws 3, or other suitable fastening means a pair of standards or frame-members 4 and 5, said standards or frame-members being

preferably provided with oppositely placed and outwardly bowed bearing portions, as 6 and 7. The said standards or frame-members 4 and 5 are usually connected by means of suitably disposed screws 8, 9 and 10 for compensating and regulating to any desired degree the space 11 between the said members. This adjustment is readily made by properly tightening or loosening, as the case requires, the screws 9 and 10. It will be noted that the screw 10 is threaded into the right-hand frame member 5, and enters into a hole in the left-hand member 4. This screw may be used to force the members away from one another, while the screw 9, 80 which is threaded into the left-hand member may be used to tighten the members in place. The said members 4 and 5, as will be seen from an inspection of said Figure 3 of the drawings, are provided with oppositely located receiving portions 12 and 13, respectively, in which are disposed suitably formed sleeves, as 14 and 15, said sleeves being made of insulating material, so that at all times the two standards or frame-members will be electrically disconnected from devices mounted on the sleeve, as will be clearly evident.

Suitably disposed in the respective insulators or sleeves 14 and 15 are tube-like elements, as 16 and 17, provided with discs 18 and 19 respectively, the respective discs carrying suitable diaphragms, as 20 and 21, which are provided with suitable and oppositely disposed contacts 22 and 23, substantially as shown. The outer or opposite end-portions of the tubes 16 and 17 extend from the respective insulators 14 and are here shown as being screw-threaded, as at 24 and 25, for securing the parts in their assembled relations by means of the washers or discs 26 and 27 and the tightening nuts 28 and 29 screwed upon the respective screw-threaded portions 24 and 25 of said tube-like elements 16 and 17.

These tubes are each to be connected to an end of the tubing which extends throughout the protected area. One of the forms of construction suitable for the purposes of the present invention will now be described.

As shown, the end-portions of the respective elements 16 and 17 projecting slightly beyond the outer faces of the respective nuts 28 and 29 are internally screw-threaded, as at 30 and 31 for the reception of the screw-threaded shanks of a pair of screws, as 32 and 33, said screws being formed with annular grooves 34 and longitudinally extending slots or channels 35, all arranged as shown in said Figure 3 of the drawings, and for the purposes to be presently more fully set forth. Suitably disposed upon each screw 32 and 33 are a pair of insulating packing sleeves, as 36 and 37, for insulatively mounting the devices 38, which

connect the respective tubes 16 and 17 with the shock-absorbing and breather devices to be described.

As here shown, each device 38 comprises a main body 39 formed with a laterally extending opening 40 by means of which said devices are fitted upon said sleeves 36 and 37 and are firmly secured in their operative positions thereon by means of the hereinabove mentioned screws 32 and 33. As shown, the lower portion of each body 39 has a small duct or passage-way, as 41, leading from the annular groove 34 to the lower end-portion of said body providing intakes 15 through which the air is breathed or taken in to fill the pneumatic tubing of the system, normally, with air under atmospheric pressure. That the taken-in air may be free from dust and moisture, (the air owing to 20 atmospheric conditions at various times containing more or less dust and moisture,) chambered devices, as 42, may be employed, substantially in a manner as represented in Figure 1 of the drawings, each device being 25 provided with a suitable material, as 42', through which the air has to pass and any dust and moisture removed therefrom. In its upper portion, each body 39 is also provided with another duct or passageway, as 30 43, also leading from the annular groove 34 in an upward direction and terminating in the upper end-portion of said body 39, and communicating with a shell or casing, as 44, of the proper length, said chamber being 35 closed at its upper end by means of a cap 45, or other suitable means, to provide a proper shock-absorbing or relief chamber 46. In communication with the duct or passageway 43 of each body 39, is a laterally extending 40 inlet duct 47, and suitably connected with said ducts 47 are the respective ends of a pneumatic tubing 48, of a fire-alarm system or temperature-indicator, substantially as shown in Figures 1 and 3 of the drawings.

45 The opening between the relief chamber 46 and the passageway 43 is considerably larger than the slots or channels 35 intermediate the passageway 43 and the diaphragm. In this way the in-coming air brought about 50 by increase of volume of air in the tubing 48 is directed more easily into the shock-absorbing chambers and is to a slight extent hindered in exerting pressure on the diaphragms.

55 As shown in said Figure 1, there is electrically connected with the complete detector-device 1, by means of circuit-wires 49 and 50, an alarm-indicator, as 51, electric current being supplied by means of a source 60 of electrical energy, as a battery 52, and the circuit being closed when contact is made by the contact-points 22 and 23, of the respective diaphragms 20 and 21, when they become active due to an expansion of the air to 65 the desired degree in the tubing 48.

Under normal conditions where the temperature is undergoing the usual changes, the air inside the tubing is maintained at atmospheric pressure by reason of the leaks which permit air to enter into or leave the 70 system as occasion demands. In breathing in and out this air it is compelled to pass through chambers 42, which are provided with suitable material to strain out dust and to absorb moisture so that there is no possibility of dust or moisture entering into the inside of the system where it has heretofore been found to accumulate and cause trouble by clogging the narrow passages in 75 the system. 80

Under fire conditions the air in the tubing is heated rapidly and the only exit for the air at increased pressure is through the vents. These vents or leaks are so small that the heated air created by fire conditions is 85 held back of the vents, thereby rapidly increasing the pressure inside the system. This increase in pressure occurs throughout the piping, the relief chambers, and back of 90 the diaphragms, expanding or bulging them 95 as to make contact and send in an alarm. By providing two diaphragms which are adapted to move toward one another it will be noted that the contact can be made more quickly than would be possible with a single 100 diaphragm. Should the tubing be accidentally opened to the outside air, as by a break in the tubing or a leak, each side of the detector would then be connected to a length 105 of small diameter tubing having an open end. Under fire conditions the air in this tubing would be heated and, in endeavoring to escape through the open end of the tubing, would necessarily build up considerable 110 pressure to overcome the frictional resistance to movement of the air along the tubing. This built up pressure is certain to 115 actuate the alarm, if the longer length of tubing, or if both lengths, are in the fire zone. Likewise, should the tubing, for any 120 reason, be closed, there would be no dead end exposed to the fire. The system could then operate in the same manner as the systems having a single diaphragm and tube with closed end. From the foregoing it will therefore be apparent that, under fire conditions, the present system has increased reliability of operation, due to the duplication of pressure responsive devices or dia-

125 phragms.

Temporary shock conditions may occur in the protected area for various reasons. The air in a portion of the tubing may be rapidly heated, as for example, by a forge fire, the opening of a furnace door, or the turning on of steam to heat a cold building. These sudden increases in temperature about a portion of the tubing will, of course, affect the air inside the tubing, causing it to 130 suddenly expand. This expansion of air

in the tubing is transmitted toward the ends of the tubing, building up pressure all along the line. The increase in pressure, however, caused by these sudden temporary shocks 5 is not permitted to reach the diaphragms. Instead of reaching the diaphragms it is dissipated in the relief or shock-absorbing means, which may be provided by interposing into the system chambers of suitable size 10 to absorb shocks of a predetermined value. The size of these chambers will depend upon the length of the tubing which is used in the installation, the capacity of the vents, the 15 sensitiveness of the diaphragms, and the character of shocks which are expected. They may be located, as indicated in the drawings, immediately adjacent the leak devices or elsewhere in the system if desired, the former, however, being in general, a 20 more convenient location for the chambers.

The provision of shock-absorbing means reduces the likelihood of false alarms from industrial shock heats of sudden rates of temperature rise, occurring at any part of 25 the tubing circuit. The pressure generated by the accidental heat expands into the entire tubing system including the additional space provided by the relief chambers. The resulting pressure is correspondingly less 30 than it would have been without the relief chambers.

The use of a pair of opposed diaphragms permits the making of contact only when the sum of the individual pressures on each 35 diaphragm equals or exceeds a set value. This construction reduces the likelihood of false alarms from industrial shock heats, particularly those occurring near one end of the tubing system. The pressure thus 40 established will bulge the adjacent diaphragm at once, but before it can be communicated through the tubing system to the other diaphragm the pressure becomes reduced both on account of being absorbed 45 by the capacity of the whole tubing circuit, and also by loss through the vents. By the time the distant diaphragm becomes affected, the total pressure on the two diaphragms has been reduced and may now 50 be so low that the diaphragms remain out of contact with each other. Thus a pressure which at the beginning was large enough to affect the adjacent diaphragm appreciably, may not cause a fire alarm. 55 This design also tends to suppress false alarms from industrial heating resulting in low rates of rise of temperature, as well as shock heats, particularly those occurring near one end of the tubing system, for the 60 same reasons as above described. The use of the opposed diaphragms also results in a large break distance between diaphragms, and a more rapid breaking of the circuit as the pressure falls off in each diaphragm; 65 both effects tending to improve the switch-

ing performance of the diaphragm contact points.

It is obvious that in event of a fire the sounding of a fire alarm will not occur until the fire has reached such proportions as to produce greater pressures in the tubing systems than those arising from industrial heats for which the system has previously been adjusted. This delay, however, is not of long duration, being only a few seconds, 70 which is of no practical consequence in obtaining the actual fire alarm.

It is obvious that my invention may be embodied in many forms and constructions, and I wish it specifically understood that the particular form shown is but one of the many forms which may be used. Various modifications and changes being possible, and possibly advantageous, I do not limit myself in any way with respect thereto. 80

I claim:—

1. In a fire-alarm system, tubing extending throughout an area to be protected, an electrical contact-establishing means connected with the tubing of the system so as to close contact upon an increase in air pressure, breather-means for conveying air normally under atmospheric pressure into said system, a relief chamber, and means for conveying expanded air from the tubing 90 into the relief chamber, said relief chamber being adapted to relieve abnormal fluctuations of pressure in said tubing without actuating said electrical contact-establishing means. 95

2. In a fire-alarm system, tubing extending throughout an area to be protected, an electrical contact-establishing means connected with the tubing of the system so as to close contact upon an increase in air pressure, breather-means for conveying air normally under atmospheric pressure into said system, and a relief chamber communicating with the tubing, said relief chamber being adapted to relieve abnormal fluctuations of pressure in said tubing without actuating said electrical contact-establishing means. 105

3. In a fire-alarm system, tubing extending throughout an area to be protected, an electrical contact-establishing means connected with the tubing of the system so as to close contact upon an increase in air pressure, breather-means for conveying air normally under atmospheric pressure into said system, and a relief chamber communicating with the tubing adjacent the electrical contact-establishing means, said relief chamber being adapted to relieve abnormal fluctuations of pressure in said tubing without actuating said electrical contact-establishing means. 115

4. In a fire-alarm system, tubing extending throughout an area to be protected, and a detector having an inlet connected to an 120 125 130

end of the tubing of the system, an air passage leading from said inlet, a vent for conveying air normally under atmospheric pressure into said passage, a relief chamber communicating with said passage for absorbing shocks produced by temporary or sudden expansions of air in said system, and for retaining the expanded air until it is dissipated through said vent, said passage 10 also leading to a device responsive to pressures in excess of the absorbing capacity of the relief chamber, and an electrical contact operable by the device.

5. In a fire-alarm system, tubing extending throughout an area to be protected, and a detector having two inlets, each connected with an opposite end of the tubing of the system, an air passage leading from each inlet, two vents for conveying air normally 20 under atmospheric pressure into said passages, relief chambers each communicating with one of said passages for separately absorbing shocks produced by temporary or sudden expansions of air in said system, and for retaining the expanded air until 25 it is dissipated through said vents, each of said passages also leading to a device spaced from the other device, said devices being responsive to pressures in excess of the absorbing capacity of the corresponding relief chamber, and an electrical contact operable by the devices.

6. In a fire-alarm system, or the like, the combination with a pneumatically-operated 25 circuit-controlling means provided with an inlet, and a pneumatic fire-detecting element comprising a relatively long air-filled tube of small diameter, of a relief chamber interposed between said detecting element 40 and said inlet, of capacity to receive expanded air due to temporary abnormal fluctuations of temperature and retard transmission of pressure therefrom to the circuit-controlling means until a sufficient 45 increase of temperature has existed for a sufficient time to produce a predetermined normal working pressure in said pneumatically-operated circuit-controlling means.

7. In a fire-alarm system, or the like, 50 a pneumatically operated contact-establishing means, combined with independent relief means adapted to receive expanded air caused by temporary or sudden shock-conditions to prevent operation of the contact-establishing means, except at predetermined 55 degrees of expansion.

8. In a fire-alarm system, or the like, a pneumatically operated contact-establishing means, and a vent adapted to dissipate 60 expanded air, combined with independent relief means adapted to receive expanded air caused by temporary or sudden shock conditions to prevent operation of the contact-establishing means except at predetermined 65 degrees of expansion.

9. In a fire-alarm system, tubing extending throughout the area to be protected, electrical contact-establishing means connected with the tubing to make contact upon increase of pressure therein, breather 70 means having a restricted leak for conveying air under atmospheric pressure into or out of the tubing, and shock-absorbing means connected with the tubing and of a capacity in proportion to the capacity of 75 the tubing to absorb shocks below a predetermined value whereby the electrical contact-establishing means is unaffected.

10. In a fire-alarm system, tubing extending throughout the area to be protected, 80 a leak duct or vent for the tubing, a device connected with the tubing, an electrical circuit adapted to be closed by movement of the device produced by increase in air pressure, and shock-absorbing means associated 85 with the tubing, said shock-absorbing means being adapted to absorb sudden or temporary shocks in excess of the capacity of the vent and thereby prevent the building up of a resulting pressure back of the 90 device to close the circuit.

11. In a fire-alarm system, tubing extending throughout the area to be protected, contact carrying diaphragms each connected to an end of the tubing, the diaphragms 95 being so juxtaposed that the contacts are moved toward one another upon expansions of either diaphragm whereby the spacing of the contacts is an inverse function of the sum of the pressures exerted on the diaphragms, and a vent associated with each diaphragm to permit the air pressure back of the diaphragm to become atmospheric independent of the pressure back of the 100 other diaphragm.

12. In a fire-alarm system, tubing extending throughout the area to be protected, contact carrying diaphragms each connected to an end of the tubing, the diaphragms being so juxtaposed that the contacts are 110 moved toward one another upon expansion of either diaphragm whereby the spacing of the contacts is an inverse function of the sum of the pressures exerted on the diaphragms, a vent associated with each diaphragm to permit the air pressure back of the diaphragm to become atmospheric independent of the pressure back of the other diaphragm, and shock absorbing 115 means adapted to absorb sudden or temporary shocks in excess of the capacity of the vents and thereby prevent the building up of a resulting pressure back of the diaphragms to close the circuit.

13. In a fire-alarm system, tubing extending throughout the area to be protected, contact carrying diaphragms each connected to an end of the tubing, the diaphragms being so juxtaposed that the contacts are moved 120 toward one another upon expansions of 125

either diaphragm whereby the spacing of the contacts is an inverse function of the sum of the pressures exerted on the diaphragms, a vent associated with each diaphragm to permit the air pressure back of the diaphragm to become atmospheric independent of the pressure back of the other diaphragm, and means associated with each vent for preventing foreign matter from 10 entering the system.

14. In a fire-alarm system, tubing extending throughout an area to be protected, and a detector having two inlets, each connected with an opposite end of the tubing of the 15 system, an air passage leading from each inlet, breather-means for conveying air, normally under atmospheric pressure, to each of said passages, said breather-means including chambers and means therein to prevent 20 foreign matter from entering the system, each of said passages also leading to a diaphragm spaced from the other diaphragm.

15. In a fire-alarm system, tubing extending throughout an area to be protected, and a detector having an inlet connected to an 25 end of the tubing of the system, an air passage leading from said inlet, breather-means for conveying air, normally under atmospheric pressure, to said passage, said breather-means including a chamber and means therein to prevent foreign matter from entering the system, said passage also leading to a diaphragm, and an electrical 30 contact operable by the diaphragm.

16. In a detector for fire-alarm systems, or the like, in combination, an electrical contact-establishing means provided with an inlet connectible with the tubing of the system 40 so as to be operable by air-pressure, means for conveying expanded air to the same, and a relief chamber interposed between said inlet and said air-conveying means, said relief chamber being adapted to relieve abnormal 45 fluctuations of pressure in said air-conveying means.

17. In a detector for fire-alarm systems, or the like, in combination, a pair of oppositely placed contact-making diaphragms, 50 means for leading expanded air against said diaphragms, and means comprising shock-absorbing chambers connected with said air-conveying means, said chambers being adapted to receive expanded air caused by 55 temporary or sudden shock-conditions.

18. A detector for fire-alarm systems, or the like, comprising a frame, a pair of oppositely placed diaphragms mounted on said frame, said diaphragms being provided with 60 oppositely disposed contacts, and means for leading expanded air against said diaphragms so as to expand the same.

19. A detector for fire-alarm systems, or the like, comprising a frame, a pair of oppositely placed diaphragms mounted on said 65

frame, said diaphragms being provided with oppositely disposed contacts, means for leading expanded air against said diaphragms so as to expand the same, and shock-absorbing chambers connected with said means for leading the expanded air to said diaphragms. 70

20. A detector for fire-alarm systems, or the like, comprising a frame, a pair of oppositely placed diaphragms mounted on said 75 frame, said diaphragms being provided with oppositely disposed contacts, means for leading expanded air against said diaphragms so as to expand the same, and shock-absorbing and air-equalizing means connected with said means for leading the expanded air to said diaphragms, comprising a member having a passage communicating with the air-leading means, and a chambered shell connected with each member, each member being 80 provided with a fixed vent.

21. A detector for fire-alarm systems, or the like, comprising a frame provided with two oppositely disposed bearing-portions, insulating sleeves mounted in said bearing- 90 portion, tubes mounted in said sleeves, flexible diaphragms mounted upon the oppositely disposed end-portions of each of said tubes, said diaphragms being provided with oppositely disposed contacts, shock-absorbing 95 and air-equalizing means associated with the tubes, and means for leading air into said shock-absorbing means.

22. A detector for fire-alarm systems, or the like, comprising a frame provided with 100 two oppositely disposed bearing-portions, insulating sleeves mounted in said bearing-portions, tubes mounted in said sleeves, flexible diaphragms mounted upon the oppositely disposed end-portions of each of said 105 tubes, said diaphragms being provided with oppositely disposed contacts, shock-absorbing and air-equalizing means associated with the tubes, comprising a member having a passage communicating with each tube, a chambered shell connected with each member, each member being also provided with a vent, and means for leading air into each member and the associated shell. 110

23. A detector for fire-alarm systems, or the like, comprising a pair of frame-members, means for connecting the same, said frame-members being provided with bearing-portions, insulating sleeves mounted in said bearing-portions, tube-like elements 115 mounted in said sleeves, flexible diaphragms mounted upon the oppositely disposed end-portions of said tube-like elements, said diaphragms being provided with oppositely disposed contacts, screws connected with and extending from the opposite end-portions of said tube-like elements, said screws being provided with annular grooves and longitudinally extending channels leading from said annular grooves into the tubular por- 120 125 130

tions of said tube-like elements, air-equalizing means mounted upon each screw and in communication with the grooves and channels of said screws, and means for leading 5 air into said equalizing means.

24. A detector for fire-alarm systems, or the like, comprising a pair of frame-members, means for connecting the same, said frame-members being provided with bearing-portions, insulating sleeves mounted in 10 said bearing-portions, tube-like elements mounted in said sleeves, flexible diaphragms mounted upon the oppositely disposed end-portions of said tube-like elements, said 15 diaphragms being provided with oppositely disposed contacts, screws connected with and extending from the other end-portions of said tube-like elements, said screws being provided with annular grooves and longitudinally 20 extending channels leading from said annular grooves into the tubular portions of said tube-like elements, shock-absorbing and air-equalizing means, comprising a tubular body mounted upon each screw 25 and in communication with the grooves or channels of said screws, a chambered shell connected with each body, each body being also provided with a "leak"-duct or vent, and means for leading air into each tubular 30 body and the chambered shells thereof.

25. A detector for fire-alarm systems, or the like, comprising a frame, an electrical contact-establishing means, a tube mounted in said frame, a flexible diaphragm mounted upon said tube and connected to said electrical contact-establishing means, means for leading expanded air into said tube, and a shock-absorbing and air-equalizing means in communication with said tube and said 40 air-leading means.

26. A detector for fire-alarm systems, or the like, comprising a frame, an electrical contact-establishing means, a tube mounted in said frame, a flexible diaphragm mounted upon said tube and connected to said electrical contact-establishing means, means for leading expanded air into said tube-like element, and an air-equalizing means comprising a member having a passage communicating with said tube, and a moisture extracting means connected with said member.

27. In a detector for fire-alarm systems or the like, in combination, an electrical contact-establishing means, means for conveying expanded air to the same, means comprising a shock-absorbing chamber in communication with said air-conveying means, said chamber being adapted to receive expanded air caused by temporary or sudden shock-conditions, and breather-means for conveying air, normally, under atmospheric pressure to said means for conveying such expanded air.

28. In a detector for fire-alarm systems,

or the like, in combination, a pair of oppositely placed contact-making diaphragms, means for leading expanded air against said diaphragms, means comprising shock-absorbing chambers in communication with 70 said air-conveying means, said chambers being adapted to receive expanded air caused by temporary or sudden shock-conditions, and breather-means for conveying air, normally, under atmospheric pressure to said means for conveying such expanded air.

29. In a detector for fire-alarm systems, or the like, in combination, a pair of oppositely placed contact-making diaphragms, means for leading expanded air against the 80 diaphragms, means for bodily moving one of the diaphragms and the corresponding conveying means to adjust the spacing between the diaphragms, and means comprising shock-absorbing chambers connected 85 with said air-conveying means, said chambers being adapted to receive expanded air caused by temporary or sudden shock-conditions.

30. A detector for fire-alarm systems, or the like, comprising a frame, a pair of oppositely placed diaphragms mounted on said frame, said diaphragms being provided with oppositely disposed contacts, means for bodily moving one of the diaphragms 90 to adjust the spacing between the diaphragms, and means for leading expanded air against said diaphragms so as to expand the same.

31. In a detector for fire-alarm systems, or the like, in combination, a pair of oppositely placed contact-making diaphragms, means for separately leading expanded air against each of said diaphragms, means comprising shock-absorbing chambers in 100 communication with said air-conveying means, said chambers being adapted to receive expanded air caused by temporary or sudden shock-conditions, adjustable mounting devices for the diaphragms to permit 110 the bodily movement of the diaphragms to adjust the spacing therebetween, and breather-means for conveying air, normally, under atmospheric pressure to each of 115 said means for conveying such expanded air.

32. A detector for pneumatic-compensating fire-alarm systems, having two inlets each connectible with an opposite end of the tubing of the system, an air passage leading 120 from each inlet, two vents for conveying air normally under atmospheric pressure into said passages, relief chambers each communicating with one of said passages for separately absorbing shocks produced by 125 temporary or sudden expansions of air in said system, and for retaining the expanded air until it is dissipated through the vents, each of said passages also leading 130 to a diaphragm spaced from the other dia-

phragm, said diaphragms being responsive to pressures in excess of the absorbing capacity of the corresponding relief chamber, an electrical contact operable by the 5 diaphragms, and mountings for the diaphragms to permit the adjustment of the spacing between the diaphragms.

33. A detector for fire-alarm systems, or the like, comprising a frame, a pair of 10 oppositely placed diaphragms mounted on said frame, said diaphragms being provided with oppositely disposed contacts, means for leading expanded air against said diaphragm so as to expand the same, shock 15 absorbing and air-equalizing means connected with said means for leading the expanded air to said diaphragms, comprising a member having a passage communicating with the tube, a chambered shell connected with 20 each member, each member being provided with a fixed "leak"-duct or vent, a chamber surrounding each "leak"-duct or vent, and means in the chamber for preventing foreign matter from entering the system.
34. In a detector for fire-alarm systems or the like, in combination, an electrical contact-establishing means, means for conveying expanded air to the same, means comprising a shock-absorbing chamber in communication with said air conveying means, 30 said chamber being adapted to receive expanded air caused by temporary or sudden shock-conditions, and breather-means for conveying air, normally, under atmospheric pressure to said means for conveying such expanded air, said breather-means including 35 a chamber and means therein to prevent foreign matter entering the system.
35. A detector for pneumatic-compensating fire-alarm systems, having an inlet con- 40

nectible with the tubing of the system, an air passage leading from said inlet, a vent for conveying air normally under atmospheric pressure into said passage, a relief chamber communicating with said passage 45 for absorbing shocks produced by temporary or sudden expansions of air in said system, and for retaining said expanded air until it is dissipated through said vent, said passage also leading to a diaphragm responsive to pressures in excess of the absorbing capacity of the relief chamber, an electrical contact operable by the diaphragm, a chamber surrounding each vent, and means in the chamber for preventing foreign matter from 50 entering the system.

36. A detector for pneumatic-compensating fire-alarm systems, having an inlet connectible with the tubing of the system, an air passage leading from said inlet, a vent for conveying air normally under atmospheric pressure into said passage, a relief chamber communicating with said passage for absorbing shocks produced by temporary or 55 sudden expansions of air in said system, and for retaining said expanded air until it is dissipated through said vent, said passage also leading to a diaphragm responsive to pressures in excess of the absorbing capacity 60 of the relief chamber, said passage having a constriction between the diaphragm and the connection to the relief chamber, and an electrical contact operable by the diaphragm.

In testimony, that I claim the invention set forth above I have hereunto set my hand this 25th day of July, 1918.

JOSEPH H. SCHARFF.
